UNITED STATES PATENT OFFICE.

GUY T. FOSTER, OF DAYTON, OHIO, ASSIGNOR TO LOCOMOTIVE ECONOMIZER CORPORATION, OF NEW YORK, N. Y., A CORPORATION OF DELAWARE.

SMOKE BOX OF LOCOMOTIVES.

Original application filed April 27, 1925, Serial No. 26,167. Divided and this application filed July 9, 1926. Serial No. 121,326.

My invention relates to improvements in smoke-box of locomotive. This application constitutes a division of an application for United States Letters Patent, Serial No. 5 26,167, filed by me April 27, 1925, and allowed January 16, 1926.

In the accompanying drawings Fig. I shows, in horizontal section, the forward end of a locomotive boiler and the smoke box of 10 the locomotive in which embodiment of my present invention is found. Figs. II and III are views to larger scale, and show in longitudinal and in transverse section the detail in which my present invention centers.

15 The smoke-box of the locomotive boiler is indicated by the numeral 1, the boiler itself by 2. The boiler is here shown to be of usual type, penetrated by tubes 10 for the passage of the hot products of combustion. These 20 tubes extend from the fire-box in the rear (not shown) to the smoke-box 1 at the front. A smoke-stack 5 leads from the smoke-box. A smoke-stack extension 4 and the steam exhaust 3 direct and impel the stream of the 25 products of combustion through the smoke-stack.

30 A certain partitioning within the smoke-box causes the stream of the products of combustion advancing from the boiler flues to divide on a vertical and medial line, and to flow forward in two branches, spread apart laterally at either side of the smoke-box. Reaching the anterior end of the smoke-box, these divided branches turn inward, meet, and 35 then flow rearward in a united, centrally arranged stream. This united, rearward-flowing stream comes at length under the influence of the jet of fluid which is projected from the steam-exhaust 3. Caught up by this 40 jet, the direction of flow is changed, and the stream of gases is swept out through the smoke-stack.

45 A feed-water heater is made up of units so placed as to achieve relatively great heat absorption from the flowing stream of hot gases and at the same time to present relatively little obstruction to the flow. That feed-water heater constitutes the subject matter of the application of which this is a division, referred to above. Suffice it here to say that the heater here shown includes three units, consisting each of a header and circulation pipes. The three headers are designated 6, 6, and 16, and the three sets of circulation pipes 7, 7,

and 17. It will be perceived that the header 55 16 is approximately triangular in shape and constitutes a dividing element, causing the stream of the products of combustion which advances through the boiler tubes to separate and to flow in lateral bifurcations, forwardly 60 at either side of the smoke-box. The circulation pipes 17 which extend rearward from header 16 enter certain of the boiler flues 10. The headers 6 of the two other heater units are forwardly placed, at the front end of the 65 smoke-box and on either side, and the circulation pipes 7 which extend from them extend rearwardly into the forward flowing branches of the divided stream. The connections for the circulation of water through these heater 70 units and from them to the boiler constitute no part of my present invention. They are described in the companion application to which allusion has been made.

Two vertically standing partition plates 9, 75 spaced apart, extend, one on either side of the central vertical plane of the boiler, their rear edges engage the header 16 of the rearwardly arranged heater unit, and their forward edges are spaced at an interval to rearward 80 of the headers 6 of the two forwardly arranged heater units. They rise from the bottom of the smoke-box to a horizontally arranged partition plate 8. The plate 8 extends from side to side, and along its opposite edges is united to the side walls of the 85 smoke-box. In this particular installation a curtain wall 30 is introduced, defining in the upper part of the structure a space in front of the boiler proper, and to rearward of the 90 smoke-box. The aforesaid plate 8 extends forwardly from the curtain wall 30 toward the front end of the smoke-box, as far as may be found desirable. In the exemplification given, the plate 8 extends to the headers 95 6 of the forwardly placed heater units. It will be perceived that these partitions 8 and 9, together with the headers of the heater units, define the course of the stream of hot gases which emerges from the boiler flues 10, 100 and cause the stream to flow in the course already indicated.

The plates 9, at the forward edges, are extensible and retractible, and to that end are provided with extensions 19. Union of extensions 19 with plates 9 themselves may conveniently be effected by bolts 20 and as a provision for the extensibility defined, the

bolt-holes in one or both parts may be elongated into slots 21. This adjustable feature permits minute variation of the effective length of the partition walls 9, and by making adaptation here to the particular condition of service, the best conditions of draft may be established and in substantially all cases the efficiency of the locomotive may appreciably be increased.

10 A screen 22 is provided in the passageway, to effect the breaking up of large cinders. This screen is arranged in best position across the passageway between plates 9, and perpendicularly to the line of flow, or substantially so. In Fig. I this screen 22 is shown to be immediately carried by the extensions 19 of the side plates. A more elaborate and more efficacious mounting of the screen is shown in Figs. II and III. The 15 screen 22 is here shown mounted in a frame 31. The frame is provided with arms 32 by which it is pivotally mounted on a shaft 33. Shaft 33 is carried by opposite plates 9 (or, if preferred, by the extensions 19). Additionally, a frame 34 with inwardly extending flanges 35 is rigidly secured between the opposite plates 9. The screen in its carrying frame 31, otherwise free to swing on shaft 33, is limited to a narrow range of swing by abutment against the flanges 35. The arrangement is clearly shown in Fig. III. Such mounting of the screen with provision for swing within a narrow range, limited by striking against flanges 35 of the rigid frame, 20 has functional value. When the locomotive is in operation the pulsations due to the intermittent escape of steam through nozzle 3 will effect a vibration of the screen in its mounting. To the extent that the screen may

be clogged, the force due to steam escape will 40 be more effective in causing vibration. Additionally, the jolt of travel tends to cause the screen to swing. The screen vibrating under these conditions is repeatedly knocked by 45 striking against the flanges 35, and this knocking tends to loosen cinders and soot, which, settling upon it, might cake and clog it. An additional feature of advantage of the construction particularly shown in Figs. II 50 and III, is that the shaft 33 may be made readily removable, so the screen may be taken out and replaced without difficulty, giving access to the space beyond for purposes incident to service.

55 I claim as my invention:

1. In a locomotive structure, a smoke-box and a smoke-stack opening from the smoke-box, a passageway formed within the smoke-box and leading to the smoke-stack, a stop stationary in the passageway, and a screen 60 extending transversely across the passageway and freely movable to and from abutment upon said stop.

2. In a locomotive structure, a fire-tube boiler, a smoke-box into which the boiler tubes open, and a smoke-stack opening from the smoke-box, a passageway formed within the smoke-box and leading to the smoke-stack, a frame with inturned flanges 65 rigidly mounted on the passageway walls and a framed screen pivotally mounted in the passageway and freely movable through a limited range between opposite positions of abutment upon the flanges of the frame first named.

70 75 In testimony whereof I have hereunto set my hand.

GUY T. FOSTER.
